JOSEPH A. STUBKJARE, OF BIGTIMBER, MONTANA, ASSIGNOR OF ONE-HALF TO ELNOR O. OVERLAND, CLARENCE FLATTUM, AND OSCAR A. NEPSTAD, ALL OF BIGTIMBER, MONTANA

COOLING APPARATUS

Application filed December 21, 1931. Serial No. 582,478.

My invention relates to a dual refrigerating or cooling apparatus, the purpose of which is to simultaneously lower the temperature of rooms in a building and to cool 5 vegetables, cream, butter and any other perishable articles. A single apparatus accomplishes both purposes, the main device comprising a chamber in which an air-blown continuous spray of water is used, said chamber 10 including a container for food stuffs, etc., and accessible without exposure to the cooling means.

Further advantages and the use of my article are hereinafter fully set forth, reference 15 being had to the accompanying drawing, in which:

Fig. 1 is a top or plan view of my cooling apparatus with small parts of the main cover broken out to expose certain details.

Fig. 2 is a longitudinal sectional elevation about as on line 2-2 in Fig. 1.

Fig. 3 is a detail view of an air outlet with flexible positioning means to direct cool air from the apparatus into a room at any desired angle.

Referring to the drawing by reference numerals, 5 designates an elongated main compartment or housing shown as of box-like proportions and having a water-tight cover 30 6. At one end is an opening in which is fixed a tube 7 leading from a centrifugal blower 8 rotated by a suitable electric motor 9 of the kind adapted to be run at various selective speeds. Intermediate the blower and the 35 casing 5 a water intake pipe 10 is connected at 11, said pipe having suitable water flow regulating means such as the valve 12.

The current of air generated by the fan is forced through pipe 7 toward the casing, 40 water from pipe 10 mixing in said air current and is sprayed into the casing with any required force.

Within the casing is a triangular compartment 13, the apex of which is in proximity 45 to the inlet of pipe 7, the angular sides of the

compartment being in the path of the forced spray which cools the walls of the compartment. Said compartment is a water tight container for vegetables, fruits, preserves, etc., an opening being provided in the cover and 50 which is normally closed by suitable means such as the hinged lid 13 C.

Each side of the triangular compartment I provide a row of parallel deflectors 14-15 of which alternate ones 14 are fixed to and extend angularly from the sides of the said compartment and the other ones 15 are fixed to the inner sides of the side walls of the main casing. The deflectors nearest the intake end of the casing are comparatively low and the others relatively higher toward the rear of the casing. The outer deflectors terminate in spaced relation to the food compartment and the inner deflectors terminate in spaced relation to the side walls for the purpose of 65 guiding the water cooled air currents in a tortuous path as designated by arrows 16 to the rear part of the main casing.

17 is an outlet pipe extending from the rear end of the casing to one or more rooms of 70 a house.

The deflectors 14-15 are each preferably a curtain of any suitable moisture accumulating material, each serving as a rigid wick partially immersed in a volume of water 22 75 in the bottom of the casing and said volume remaining constant by simply providing an outlet or overflow pipe 23 at a desired height.

The deflectors 14-15 being of variable, stepped up heights it is obvious that all of 80 them will be contacted by the spray from intake 7 completely saturating the wicks, and the latter will cool the volume of air passing over and between them as described.

Between the rearmost deflector, the walls 85 of the casing and the exterior rear parts of the container 13 is formed a comparatively large chamber C from which cooled air circulates through duct 17. The water spray or particles projected from intake 7 is calculated 90

to be mostly settled by the time the water-cooled air reaches the said chamber and cooled but comparatively dry air enters the conductor pipe 17. Said pipe may lead to one or 5 more terminal outlets of which a preferred form is shown in Fig. 3. 18 is a wall in which pipe 17 leads to a flexible tube 19 conducting the cool air to a suitable outlet 20 which may be directed as desired into a room 10 which may be directed as desired into a room to be cooled.

I have now fully disclosed a preferred embodiment of and the use of my cooling apparatus. It is obvious that the contents of container 13 is accessible only by raising lid 14. 15 In Fig. 1, 21 designates a screen or other foraminous fixed intake pipe cover for breaking up into fine particles the water passing therethrough. This part 21 may be used or omitted as may be desired.

20 It will now be readily understood that my device provides for a continuous supply of water cooled air in one or more rooms of a house, the air cooling means simultaneously cooling the container 13 to keep foodstuffs, 25 etc., in desirable condition.

Modifications of structure may be embodied without departing from the scope and spirit of the invention.

A condition not hitherto described is that 30 the combination wick-vanes 14—15 are at all times completely saturated, the capillary action of the partly immersed wicks keeping them always moist in their areas exposed to the air current from pipe 7. The constant 35 spray of cold water further saturates wicks and cools the entire interior of the main chamber and provides the supply of cool air required as described.

I claim:

40 1. In a dual cooling apparatus of the class described including an elongated quadrangular main chamber with a forced air intake in one end and a cold air outlet at the opposite end, a storage chamber within said main 45 chamber and provided with means for access through the top of the main chamber, and a liquid supply pipe connected to said air intake; said storage chamber of triangular form and fixed with its apex in proximity 50 to said intake of the main chamber, upright wicks in said main chamber and fixed in parallel spaced relation, in two groups, one group at each side of the storage chamber and extending from near the intake end of the 55 main chamber toward the wider and rear end of the storage chamber.

2. The structure specified in claim 1 in which each said group of wicks comprises a series of members extending upward from 60 the bottom of the main receptacle, alternate wicks fixed also to the inner side wall parts of the main chamber and terminating in spaced relation to the storage chamber, the other wicks of each group fixed to the side 65 walls of the storage chamber and extending

toward the adjacent side walls and terminating in spaced relation thereto.

3. The structure specified in claim 1, in which said wick members are of progressively increased height, the members nearest the intake being low and the successive rearward wick members relatively higher, said main chamber adapted to retain a volume of water for constant immersion of all said wicks.

In testimony whereof I affix my signature. 75
JOSEPH A. STUBKJARE.
